UNITED STATES PATENT OFFICE

111,873

DESIGN FOR A MOWER REEL

Richard D. Clemson, Middletown, N. Y., assignor
to Clemson Bros., Inc., Middletown, N. Y., a
corporation of New York

Application August 19, 1938, Serial No. 79,452

Term of patent 14 years

To all whom it may concern:

Be it known that I, Richard D. Clemson, a citizen of the United States, residing at Middletown, New York, have invented a new, original, and ornamental Design for a Mower Reel, of which the following is a specification, reference being had to the accompanying drawing, which forms a part thereof, in which

Figure 1 is a perspective view of a lawn mower cutter reel embodying my design.

Figure 2 is an enlarged fragmentary view in end elevation of the same.

I claim:

The ornamental design for a mower reel, substantially as shown.

RICHARD D. CLEMSON.
